PRODUCTION OF NAPHTHENIC ACIDS

Henry B. Kellogg, Union City, and Peter J. Gaylor,
Union, N. J., assignors to Standard Oil Develop-
ment Company, a corporation of Delaware

Application February 18, 1941, Serial No. 379,486

7 Claims. (Cl. 202—57)

The present invention is concerned with the production of high quality naphthenic acids. The invention more particularly relates to the purification of naphthenic acids, especially those naphthenic acids which are segregated from petroleum oils in various refining operations. In accordance with our process, an efficient and economical method is provided for effecting the removal of objectionable impurities from naphthenic acids which heretofore have been relatively difficult to remove completely, and which have rendered naphthenic acids, particularly those secured from petroleum oil sources, unsuitable for many uses.

It is well-known in the art that petroleum oils contain naphthenic acids, which substances are segregated from the petroleum oil by various methods as, for example, from the spent caustic solutions secured during the refining of these oils. The naphthenic acids generally comprise a mixture of acidic compounds having rather complex molecular structures and containing principally carbon, hydrogen and oxygen. The molecular weights of the respective acids vary considerably. Various naphthenic acids found in petroleum are low boiling liquids while others are heavy, viscous liquids at ordinary temperatures and pressures. In general, these acids are characterized by containing at least one carboxyl group attached to the naphthenic hydrocarbon molecule. Various methods have been introduced to segregate and to purify naphthenic acids recovered from petroleum oils. For example, naphthenic acid crude fractions have been distilled under vacuum in order to segregate particularly desirable fractions. It has also been suggested that the crude naphthenic acid fractions or selected fractions be contacted with various oxides, such as manganese dioxide, chromic oxide, ferric oxide, cupric oxide, and related oxides and compounds. However, when employing these operations, it has been extremely difficult to decolorize satisfactorily the naphthenic acid constituents and especially difficult to remove the last traces of impurities which impart a disagreeable odor to the refined naphthenic acid products.

We have, however, now discovered a particularly desirable method by which naphthenic acids may be readily and efficiently deodorized and decolorized. Our process comprises contacting the crude naphthenic acids or fractions thereof with an activated copper chromite catalyst, known as "Adkins' catalyst" and prepared as disclosed in Adkins' book, "Reactions of Hydrogen," University of Wisconsin Press, 1937, pages 13 and 14. Our naphthenic acids are generally obtained from a naphthenic acid-bearing petroleum oil by washing the oil with an alkali solution such as sodium hydroxide. The process

of our invention may be readily understood by reference to the attached drawing illustrating an embodiment of the same.

A feed oil, which for the purposes of illustration is taken to be an uncracked petroleum oil fraction segregated from a naphthenic crude and boiling in the gas oil boiling range, is introduced into contacting zone 1 by means of feed line 2. In contacting zone 1 the feed oil is scrubbed with an aqueous alkali metal hydroxide solution which is introduced into zone 1 by means of feed line 3. For purposes of description it is assumed that the aqueous alkali metal hydroxide solution comprises a dilute sodium hydroxide solution. It is to be understood that zone 1 may comprise any suitable number and arrangement of units. The treated feed oil is withdrawn from zone 1 by means of line 4 and handled in any manner desirable. The spent sodium hydroxide solution is withdrawn from zone 1 by means of line 5 and passed to zone 6 in which temperature and pressure conditions are adjusted to remove water overhead by means of line 7. The concentrated sodium naphthenate solution is withdrawn from zone 6 by means of line 8 and passed into acidification zone 9 equipped with a stirrer in which the concentrated salt solution is acidified with a suitable acid introduced by means of line 10. For purposes of description, it is assumed that the acid comprises concentrated sulfuric acid. The acidified product is withdrawn from acidification zone 9 by means of line 11 and passed into distillation zone 12 in which temperature and pressure conditions are adjusted to remove the naphthenic acids and some water overhead by means of line 13. Non-volatile reaction products and other non-naphthenic acid constituents are removed as a bottoms from distillation zone 12 by means of line 14. The overhead naphthenic acid constituents are condensed in cooler 15, passed to a separator 28 wherein water is separated from the acids and drawn off at 25. The separated acids are then drawn off at line 30 and passed to distillation zone 16. A relatively small quantity of low boiling distillate is removed under vacuum through line 17, while a small quantity of relatively high boiling bottoms is removed by means of 18. A relatively large quantity of the desired intermediate boiling constituents or a so-called "heart cut" is removed by means of line 19. This intermediate boiling fraction is condensed in cooler 20 and passed to distillation zone 21 wherein it is distilled under vacuum in the presence of a copper-barium chromite catalyst, known as the "Adkins' catalyst," prepared as hereinafter described. This catalyst is introduced preferably in suspension in oil or naphthenic acid from line 19, into zone 21 by means of line 22. Temperature and pressure conditions are adjusted to remove overhead by

means of line 23 the purified naphthenic acids which are substantially colorless and freed of the obnoxious odor usually associated with such acids. This overhead product is condensed in cooler 24, withdrawn from the system by means of line 25 and further refined or handled in any manner desirable. The impurities comprising color-forming and odor-imparting substances, together with spent catalyst, are withdrawn from distillation zone 21 by means of line 26. It is to be understood that the various zones 6, 9, 12, 16, and 21 may comprise any suitable number and arrangement of units, and that the respective operations may be either adapted to a batch or to a continuous operation. Under certain conditions it may be desirable to distill the entire fraction removed overhead from zone 12 rather than a heart cut. If this operation be utilized, the overhead from zone 12 is introduced directly into distillation zone 21 by means of line 27.

It is also possible to contact naphthenic acid vapors directly with the catalyst in the form of a bed in a treating tower, rather than by contacting the liquid acids during distillation. Hydrogen or other treating gases may be present during the treatment, and the catalyst may be in powder form, or it may be formed or extruded into pellets, ribbons, etc., either with or without carriers such as clays, alumina, silica gel, etc., or mixtures thereof.

The process of the present invention may be widely varied. It may be adapted for decolorizing and deodorizing naphthenic acids secured from any source. It is, however, particularly adapted for the refining of naphthenic acids secured from a petroleum oil source, in order to produce a product of enhanced odor and color. The invention is particularly adapted for the refining of naphthenic acids secured from un-cracked petroleum oil fractions boiling in the gas oil and reduced crude ranges, which have been segregated from naphthenic crudes. In general, these petroleum oil fractions boil in the general range from about 400° F. to 900° F. or in the range from about 400° F. to 700° F.

The crude naphthenic acids may be segregated from the petroleum oils utilizing any suitable medium. It is, however, preferred to contact the petroleum oils with an alkaline solution such as that now used in the art.

Although the total naphthenic acids may be distilled in the presence of the catalyst of the present invention, it is preferred to segregate a heart cut and to treat this cut as described. This heart cut, in general, comprises the fraction consisting of 5% to 95% or even 10% to 90% cut of the crude naphthenic acids.

The catalyst used for decolorizing naphthenic acid according to the present invention is commonly known as "Adkins' catalyst" and is prepared by the following procedure:

900 ml. of a solution (at 80° C.) containing 260 g. of trihydrated copper nitrate and 31 g. of barium nitrate are added to 900 ml. of a solution (at 25° C.) containing 151 g. of ammonium dichromate and 225 ml. of 28 per cent ammonium hydroxide. The precipitate is filtered, the cake pressed with a spatula, and sucked as dry as possible. The product is dried in an oven at 75° C. to 80° C. for twelve hours and then pulverized. It is decomposed in three portions in a casserole over a free flame. In carrying out the decomposition, the powder is continuously stirred with a spatula and the heating so regulated that the

evolution of gases does not become violent. This is accomplished by heating only one side of the casserole and stirring the powder more rapidly when the decomposition starts to spread throughout the mass. During this process the color of the powder changes from orange to brown and finally to black. When the entire mass has become black, the evolution of gases ceases, and the powder is removed from the casserole and allowed to cool. The combined product is then leached for thirty minutes with 600 ml. of 10% acetic acid solution, filtered, and washed with 600 ml. of water in six portions, dried for 12 hours at 125° C., and pulverized. The yield of catalyst is 170 g. (Copper sulfate and sodium dichromate may be substituted for the corresponding nitrate and potassium salts.)

The catalyst comprising a copper-barium chromite known as the "Adkins' catalyst," prepared as described in the above identified publication, may be employed in any particle size. The amount of catalyst employed may vary widely depending upon the particular type of naphthenic acids and the concentration of the impurities present. The amount of copper-barium utilization is generally less than 10%, preferably less than 5%, based upon the weight of the naphthenic acids being treated. Particularly desirable results have been secured when the amount of catalyst employed in the distillation operation is in the range from about 0.25% to 1%.

In order to illustrate the invention further, the following examples are given, which should not be construed as limiting the invention in any manner whatsoever.

Example 1

A naphthenic acid crude fraction was prepared in the following manner:

A cracked petroleum oil which was segregated from a naphthenic crude was contacted with a dilute sodium hydroxide solution. The spent alkali was separated and water removed therefrom. The concentrated salt solution thus prepared was then contacted with concentrated sulfuric acid in order to generate the naphthenic acids from the sodium naphthenates. The acidified solution was then distilled in order to segregate the crude naphthenic acids.

The latter were then distilled under vacuum and a 10% to 88% heart cut segregated, utilizing a temperature of from 125° C. to 200° C., at 5 mm. pressure.

This cut was then treated with various metal compounds and the Robinson color of the final product determined. The results were as follows:

Mixture treated	Robinson color
Original acids	12
Original acids+0.5% cupric oxide	18.5
Original acids+0.5% chromium oxide	18.5
Original acids+0.25% cupric oxide and 0.25% chromium oxide	18.0
Original acids+0.5% Adkins' catalyst	24.25

From the above, it is apparent that neither cupric oxide nor chromium oxide nor combinations of the two oxides give anywhere near the improvement in color as that obtained with an equivalent weight of Adkins' catalyst prepared as described above.

Example 2

A crude naphthenic acid fraction prepared as described in Example 1 was treated with the catalyst of the present invention, except that the entire crude fraction was treated rather than a heart cut of the same. The distillation in the presence of the Adkins' catalyst was conducted at a temperature in the range from about 125° C. to about 180° C., at a pressure of 30 mm. The results were as follows:

Robinson color
Original (dark reddish brown) $\frac{1}{4}$ (no match)

Original + 0.5% Adkins' catalyst 18.75

Upon straight distillation the same fraction has a Robinson color of about 12, showing that the Adkins' catalyst gives a decided improvement in color. The odor of the acids was likewise greatly improved.

It is to be understood that the product produced in accordance with the present invention may be handled in any manner desirable. Antioxidants may be added in order to stabilize the treated naphthenic acids, such as by the addition of 0.001 to 0.1% of tertiary amyl phenol or similar materials.

What we claim as new and wish to protect by Letters Patent is:

1. Process for decolorizing impure naphthenic acids which comprises contacting said naphthenic acids in the presence of an activated copper barium chromite. 30

2. Process as defined by claim 1, in which said contacting operation is carried out at a temperature range from about 100° C. to 200° C.

3. Improved process for the purification of naphthenic acids recovered from petroleum oils containing the same, which comprises segregating naphthenic acids from said petroleum oils comprising distilling said naphthenic acids in the presence of a copper-barium chromite catalyst.

4. Process as defined by claim 3, in which said petroleum oil comprises an uncracked petroleum oil boiling in the gas oil boiling range, said petroleum oil being secured from a naphthenic crude.

5. Process as defined by claim 3, in which a heart cut of the naphthenic acids is distilled under vacuum in the presence of the catalyst.

6. Process for improving odor and color of crude naphthenic acid fractions, which comprises distilling said crude naphthenic acid fractions in order to segregate an intermediate boiling cut, then distilling said intermediate boiling cut in the presence of a copper-barium chromite, whereby naphthenic acids of greatly enhanced odor and color are removed overhead.

7. Process as defined by claim 6, in which said intermediate boiling cut is about the 10% to 90% fraction.
